REFRIGERATING UNIT

Matthew Patrick Fugle, Chicago, Ill., assignor to
 Commercial Coil and Refrigeration Co., Chi-
 cago, Ill., a corporation of Illinois

Application November 10, 1933, Serial No. 697,394

24 Claims. (Cl. 62—101)

The present invention relates to refrigerating apparatus and more particularly to what is known as coil boxes for cooling beverages such as beer or the like.

In refrigerating apparatus for dispensing beer, ice water, or the like, as heretofore constructed, it has been customary to provide a container for the reception of one or more coils, and to pack cracked ice in and about the coils in order to secure reasonably satisfactory results in maintaining the beer at a low temperature. Certain well known disadvantages are inherent in this form of refrigeration. Probably the greatest objection is the expense and inconvenience of providing the cracked ice. On the other hand attendants dislike the handling of ice. In some instances, however, brine or refrigerant coils have been used to cool the beverage, but, unlike the cracked ice lying against the beverage coil, the cooling medium employed would not transfer the heat from the beverage coils quickly enough, during a peak demand, to keep or hold the beverage at the desired low temperature. It seems that the cooling medium, whether water or air, will retard a quick transfer of the heat and will tend to act as an insulator temporarily when an immediate demand for the beverage requires a prompt cooling thereof. To illustrate, it has been found that when the cooling medium would be say 34° to 35° Fahr., the drawing of several glasses of beverage would immediately raise the temperature of the cooling medium to say 40° Fahr., and the beverage to 45° Fahr. If additional beverage of any amount is then drawn from the coil, its temperature continues rising to about that of the beverage entering the coil. In other words, the beverage would be drawn at a rate greater than the cooling rate of the cooling medium and the latter would be ineffective to maintain the beverage at a desired low temperature. There have been attempts to use a brine as a cooling medium so that a lower temperature might be maintained to hold the beverage at a low temperature. This has been unsatisfactory because any lower temperature of the brine will freeze the beverage and the drinking water in their coils.

One of the principal objects of the present invention is the provision of a refrigerating apparatus for cooling beverages or the like in the form of a self-contained coil box comprising a beverage coil and automatically controlled refrigeration mechanism adapted, without attention, to maintain the beverage in the coil at a predetermined low temperature and to hold it at such low temperature irrespective of the amount of bev-

erage withdrawn. In the preferred form of the invention, two compartments are provided, one for the beverage coil and one for the refrigerant coil. The control mechanism functions to circulate the cooling medium from one compartment or chamber to the other, so that, as the beverage is withdrawn at the outlet of the beverage coil, the difference in temperature at the inlet thereof will start the control mechanism and circulate the cooling medium.

Another object of the invention is the provision of improved mechanism for maintaining the beverage and other liquids on draft, such as drinking water, at a predetermined low temperature, irrespective of the amount drawn, without freezing such liquids in the coil pipes.

Another object of the invention is the provision of refrigerating apparatus of the type described wherein the cooling of the beverage and the maintenance thereof at a predetermined low temperature is controlled by thermal means responsive to temperature changes resulting from the withdrawal of the beverage at the outlet of the beverage coil.

A still further object of the invention is to accomplish the aforesaid results by the provision of a motor driven circulating means adapted to circulate the cooling medium, preferably from a compartment containing the refrigerant coil and into the compartment containing the beverage coil or coils, whereby the warmer incoming beverage at the inlet of the beverage coil will set said circulating means into operation and establish a circulating of the cooling medium.

Still further objects and advantages of the present invention will be apparent from the following description when taken in connection with the accompanying drawings forming a part hereof.

In the drawings:

Figure 1 is a top elevation of a coil box embodying my invention;

Fig. 2 is a vertical sectional view of the coil box shown in Fig. 1;

Fig. 3 illustrates a beverage cooling system employing the coil box disclosed herein;

Fig. 4 is a top elevational view of a coil box employing a slightly modified container or tank construction;

Fig. 5 is a vertical sectional view thereof;

Fig. 6 is a detailed sectional view taken on line 6—6 of Fig. 5;

Fig. 7 is a fragmentary detailed view illustrating mounting the thermally responsive element with in the inlet connection of the beer coil.

Referring in detail to the construction illustrated the coil box A has a suitable tank or container structure 1 provided with an outer top cover 2 and an inner partition 3 preferably made of any suitable heat insulation material dividing the same into compartments or chambers 4 and 5. A cooling coil 6 adapted to have a suitable refrigerant such as brine flowing therethrough is disposed in compartment 4 with its inlet and outlet connections 7 and 8 leading to a compressor 9 or other suitable source of cooling means that may be employed. Beverage coils 9 and 10 are disposed in compartment 5. Inlet connections 11 and 12 of these beverage coils 9 and 10 lead to a barrel 13 or other suitable source of beverage supply located with respect to the coil box at any convenient place in the building.

Usually installations dispensing beer have the barrels located in the basement with the compressor 26 conveniently located with respect thereto, the fluid connections leading to these parts through the floor 14. The particular manner of supplying the beverage to the coils 9 and 10 in box A is not an important feature of the invention because various methods may be used and the same results accomplished.

The outlet connections 15 and 16 of the beverage coils 9 and 10 may extend through the coil box and connect with spigots 17 conveniently located on a counter 18.

An inner cover 19 is provided for container 1 for supporting certain parts of the coil box. Cover 19 may be removably fastened by bolts 20 to the upper inner edge of container 1, while the outer cover 2 provides an enclosure for the inner cover 19 by fitting over the upper end of container 1.

Compartments 4 and 5 are provided with a suitable cooling medium, such as water, which may be circulated from one to the other compartment through upper and lower passages 21 and 22, these passages being illustrated at the upper and lower ends of partition 3, although they may be located anywhere along this partition as long as an efficient circulation of the cooling medium is obtained.

To effect this circulation of the cooling medium between the compartments 4 and 5, there is provided a thermal responsive motor driven propeller 23 arranged at one end of a by-pass housing 24. The housing 24 is conveniently located with respect to the bottom of tank 1 and the passage 22 so that this passage 22 is in effect the passage extending through the housing and forming the by-pass. Fastening means 25 may be used to secure housing 24 to the base and side of partition 3 in the compartment 4. A spider bracket 27 is bolted to by-pass housing 24 over passage 22 to carry drive shaft 28. Propeller 23 is connected to the lower end of the drive shaft 28. The drive shaft 28 extends upwardly through a sleeve 29 having a bearing 30 projecting therein which extends from inner cover 19, the bearing being enlarged at 31 and carrying anti-friction rollers if found desirable. The upper end of drive shaft 28 is furnished with a pulley 32 driven by a belt 33 or like driving connection leading from an electric motor 34. It will be noted, therefore, that the inner cover 19 acts to carry certain parts of the drive for the propeller 23, and compactly supports the motor 34 and these parts at the upper end of container 1.

It is common practice to incorporate additional smaller coils 37 in the compartment 5 for cooling drinking water. Such coils 37 may be located within a sleeve 35, as shown, or in any other con-

venient point which will effectively cool the drinking water without freezing the same.

A thermally responsive element, such as a thermostat 40, is disposed in compartment 5 in intimate contact with the inlet connections 11 and 12 of the beverage coils 9 and 10 by means of brackets 41. Thermostat 40 is arranged in the electrical circuit of motor 34 at 43 and is adapted to close this circuit to start the motor when the temperature of the inlet connections 11 and 12 10 or the beverage entering the same drops below its predetermined temperature setting. A temperature setting device 42 may be located at any convenient point with respect to container 1 so that it may be accessible to vary the temperature setting of thermostat 40 if desirable.

Container 1 may assume different forms and shapes, this being illustrated in Figs. 4 and 5, by the provision of separate tanks 45 and 46 having a connecting member 47 at the upper inner edges 20 to form upper passage 21. The inner walls 48 and 49 of tanks 45 and 46, which inner walls 48 and 49 form, in effect, partition 3, of the form of device shown in Figs. 1 and 2, are spaced apart slightly to provide an air space 50. While I 25 desire to provide air space 50 between tanks 45 and 46 as a practical matter, it will be understood that this is not necessary and that a single tank with a heat insulated partition therein, as illustrated in the aforesaid embodiment, may be used instead.

In the event separate tanks 45 and 46 are employed, a base 51 may be furnished with a by-pass 52 between these tanks at their lower ends. Base 51 may have shoulders 53 formed thereon for the purpose of receiving tanks 45 and 46 in suitable fastening relation. A perforated bracket 54 may be disposed over an extension 58 and bolted to base 51 within and at the lower end of tank 45. Bracket 54 serves to support propeller 23 and its 40 drive, including drive shaft 28. This construction is substantially the same as shown and described in Figs. 1 and 2. The opposite end of by-pass 52 opens into the bottom of container 46. Base 51 at this end of by-pass 52 is also adapted 45 to have an extension 55 acting as a mouth to direct the cooling medium coming from the refrigerant compartment directly into the interior of the beverage coils and thereby to bring it into intimate contact as soon as possible with the inlet 50 connections 11 and 12 of beer coils 9 and 10.

In both embodiments of the invention, it is desirable to provide a baffle or damper for passage 22, which will drop by gravity into closed position when the cooling medium is not circulating. Such baffle or damper is illustrated at 55 in Fig. 2 and at 56 in Fig. 5. The purpose of the baffles is to prevent a thermal circulation from one compartment to the other through either of the passages 21 and 22, when the propeller 23 is at rest and the cooling medium is not circulating, as the result of the difference in temperature of the cooling medium in these compartments.

When the propeller 23 is at rest, the level of the cooling medium in these compartments is 65 preferably slightly below the upper passage 21. If baffles 55 and 56 were not provided for the lower passage, a lowering temperature in compartment 4 would lower the temperature of compartment 5 through passage 22 and tend to freeze the beverage in coils 9 and 10. If a thermal circulation of the cooling medium did occur, it would continue independent of the control of the thermostat 40 and might lower the temperature 70 in the compartment 5 to a point which would 75

freeze the beer in the coils 9 and 10 as the result of the source of refrigeration, such as the compressor 26, continuing to operate and lower the temperature of the refrigerant in coil 6 below that which is intended or might be desirable.

In operation, the compressor 26 will operate intermittently to maintain the temperature of the refrigerant, and of course, the refrigerant coil 6, at a predetermined low temperature, say for example, at a low temperature, which will maintain the cooling medium in compartment 4 at 32° Fahr. With the cooling medium held at a temperature of say 32° Fahr., the temperature of the beverage when first withdrawn, as from spigot 17, will be approximately 38° Fahr. Thermostat 40 may operate to close the motor circuit at say a temperature of 36° Fahr., and cause the propeller 23 to circulate the cooling medium from compartment 4 into compartment 5. Due to the rate at which the beverage is drawn through the coils 9 and 10, when there is a constant demand for the beverage at spigot 17, the temperature of the beverage will rise several degrees, say to about 40° Fahr., and be maintained at such temperature irrespective of further continued demand at the spigot. This difference of temperature, as stated, will occur as a result of the time required for the heat transfer through the coils, but is so slight as to be unnoticeable by the consumer. The apparatus will, however, maintain the beer at 40° Fahr. temperature due to the fact that when there is a further continued demand for the beverage at the spigot, the propeller 23 will continue circulating the cooling medium from the refrigerant chamber 4 to the beverage coil chamber 5, and this circulation being maintained at a constant rate will hold the beverage in coils 9 and 10 at this desirable low temperature and will effect a relatively rapid transfer of heat from the beverage coils 9 and 10 to the cooling medium.

It will thus be apparent that the higher temperature beverage entering the coils 9 and 10 at their inlet connections 11 and 12 will, if it continues to be drawn through the coils as a result of a demand for the beverage at the spigots, promptly influence the thermostat 40 and cause the motor to drive propeller 23. The cooling medium entering compartment 5 through by-pass 22 from compartment 4 will act to maintain the beverage coils 9 and 10 at a constant or predetermined low temperature. Due to the efficient circulation of the cooling medium through these compartments and the promptness with which it will respond when the beverage first enters the coils 9 and 10 at their inlet connections, the beverage will be properly cooled before leaving the spigots irrespective of the continued demand at any one time.

While the positioning of thermostat 40 in close proximity to inlet connections 11 and 12 of the coils 9 and 10 is sufficient for it to be responsive to the temperature of the incoming beverage, it will be understood that this thermostat may be located in either inlet 11 or 12, such as I have shown in connection with inlet 11 in Fig. 7, or it may be located in the compartment 5 to be responsive to the cooling medium.

It will be apparent to those skilled in the art that various modifications and arrangements of the parts may be made without departing from the scope of the invention.

I claim:

1. In a refrigerating apparatus, the combination of two compartments, cover means for said

compartments, a refrigerant coil in one of said compartments, a beverage coil in the other compartment, inlet and outlet connections for said coils carried by said cover means, said coils being attached to said inlet and outlet connections so as to be removably held in said compartments by said cover means, means for circulating a cooling medium from one to the other compartment, and means responsive to the temperature of the beverage at the inlet of said beverage coil for starting and stopping said circulating means.

2. In a refrigerating apparatus, a refrigerant compartment and a beverage compartment, a refrigerant coil and a beverage coil in said respective compartments, a passage between said compartments substantially at their upper end, a passage between said compartments substantially at their lower end, a motor driven propeller for circulating a cooling medium from said refrigerant compartment through said beverage compartment, and means for positioning said motor driven propeller adjacent said lower passage, said means being provided with a passage coextensive with said lower passage through which said propeller forces the cooling medium bodily over said beverage coil.

3. A beverage refrigerating unit, comprising, in combination, two compartments, a refrigerant coil in one compartment, a beverage coil in the other compartment, said compartments having communicating passages substantially at or near their upper and lower ends and having a cooling medium circulating from the refrigerant coil compartment through the lower passage upwardly and out of the beverage coil compartment through the upper passage back into the refrigerant coil compartment, and a motor driven propeller providing said circulation, said propeller being disposed substantially in said lower passage to provide a forced circulating stream which enters said beverage coil compartment through said lower passage, said lower passage directing the forced circulating stream substantially centrally upward through said beverage coil compartment whereby to effect a continuous agitated flow surging upwardly over said beverage coil, the cooling medium entering said beverage coil compartment bodily moving the cooling medium therein in an upward direction to compel continuous displacement thereof over said beverage coil and back into said refrigerant coil compartment through said upper passage.

4. A beverage refrigerating unit, comprising, in combination, two compartments, a refrigerant coil in one compartment, a beverage coil in the other compartment, said compartments having communicating passages substantially at or near their upper and lower ends and having a cooling medium circulating from the refrigerant coil compartment through the lower passage upwardly and out of the beverage coil compartment through the upper passage back into the refrigerant coil compartment, a motor driven propeller providing said circulation, said propeller being disposed with respect to said lower passage to provide a forced circulating stream which enters said beverage coil compartment through said lower passage, said lower passage directing the forced circulating stream substantially centrally upward through said beverage coil compartment whereby to effect a continuous agitated flow surging upwardly over said beverage coil, the cooling medium entering said beverage coil compartment bodily moving the cooling medium therein in an upward direction to compel continuous displacement thereof.

- ment thereof over said beverage coil and back into said refrigerant coil compartment through said upper passage, and a thermal responsive element actuated by the temperature of the beverage entering said beverage coil for controlling the operation of said motor driven propeller.
5. A beverage refrigerating unit, comprising, in combination, two compartments having communicating passages substantially at or near their upper and lower ends and a cooling medium adapted to be circulated therethrough, a refrigerant coil in one of the compartments, a beverage coil in the other compartment, and a motor driven propeller providing said circulation, said propeller being disposed adjacent one of said passages to provide a forced circulating stream which enters said beverage coil compartment through the last said passage, the last said passage directing the forced circulating stream substantially centrally through said beverage coil compartment whereby to effect a continuous agitated flow surging through and over said beverage coil, the cooling medium entering said beverage coil compartment bodily moving the cooling medium therein in a direction to compel continuous displacement thereof over said beverage coil and back into said refrigerant coil compartment through the other passage.
6. In a refrigerating apparatus, the combination of a refrigerant compartment and a beverage compartment, a refrigerant coil and a beverage coil in said compartments, said compartments having openings at or near their upper and lower ends, communicating passages connecting said compartments at said openings, one of said communicating passages being connected to said refrigerant compartment at the opening in the lower end thereof, the other communicating passage being connected to said refrigerant compartment at the opening in the upper end thereof, and a motor driven propeller in said refrigerant compartment for circulating a cooling medium from said refrigerant compartment through its lower opening and said passage connecting thereto into said beverage compartment, said motor driven propeller being located substantially adjacent said lower opening in said refrigerant compartment for forcing a substantial flow of the cooling medium therefrom into said beverage compartment to effect an agitated flow surging through and over said beverage coil in a direction to compel continuous displacement over said beverage coil.
7. In a refrigerating apparatus of the class described, two tanks arranged parallel in a side-by-side relation, two coils arranged one in each tank and in the same direction as the tank, inlet and outlet connections for said coils, cover means carrying said connections, said coils being attached to said connections so as to be removable with said cover means from said tanks, and motor driven means including communicating passages between said tanks for establishing a forced circulation of a cooling medium therethrough.
8. In a refrigerating apparatus of the class described, two tanks having communicating passages for the circulation of a cooling medium, a beverage coil longitudinally arranged in one tank, a refrigerant coil longitudinally arranged in the other tank, a motor, a drive from said motor extending lengthwise in said refrigerant coil tank, a propeller at the end of said drive, and cover means carrying said coils and said motor in removable relation upon said tanks.
- 75 9. In a refrigerating apparatus of the class de-

scribed, two tanks having communicating passages providing for the circulation of a cooling medium substantially longitudinally and centrally through said tanks, and a coil in each tank so arranged therein with respect to said longitudinal central circulation that at least a substantial portion of each coil lies in the circulating cooling medium.

10. In a refrigerating apparatus of the class described, two tanks having communicating passages providing for the circulation of a cooling medium substantially longitudinally and centrally through said tanks, a coil in each tank so arranged therein with respect to said longitudinal central circulation that at least a substantial portion of each coil lies in the circulating cooling medium as it is forced through said tanks, inlet and outlet connections for supplying a refrigerant to one of said coils, inlet and outlet connections for supplying a beverage to the other coil, and means providing for a forced circulation of the cooling medium comprising a motor driven propeller disposed in said refrigerant coil tank substantially centrally below said refrigerant coil and above the opening of one of said communicating passages.

11. Refrigerating apparatus of the class described comprising, in combination, two tanks connected together by communicating passages adapted to provide for the circulation of a cooling medium between said tanks, cover means for closing one end of said tanks, a beverage coil in one tank, a refrigerant coil in the other tank, said cover means removably suspending said coils in said tanks, a propeller disposed in one of said tanks adapted to establish a forced circulation of the cooling medium through one tank and back to the other tank by means of said communicating passages, a motor mounted on top of said cover means, and a driving connection extending through said cover means and into one of said tanks to connect said motor with said propeller.

12. Refrigerating apparatus of the class described comprising, in combination, two tanks each having one end open, cover means for closing said open ends, a refrigerant coil suspended in one of said tanks from the under side of said cover means, a beverage coil similarly suspended in the other tank, and means for circulating a cooling medium through one tank and back through the other tank, including a motor mounted on top of said cover means, a drive extending through said cover means into said tank containing said refrigerant coil, and a propeller at the end of said drive, said tanks having openings in their bottoms and openings at or near their upper ends, and communicating passages connecting between said openings, said bottom openings providing for a substantially complete displacement of the circulating cooling medium substantially longitudinally through and centrally out of one tank and into and longitudinally through the other tank.

13. Refrigerant apparatus of the class described comprising, in combination, a pair of tanks having cover means therefor and communicating passages therebetween, an exteriorly supported motor on said cover means, a drive therefrom extending longitudinally into one of said tanks, a propeller at the end of said drive, a refrigerant coil in said tank, said refrigerant coil being supported by said cover means above said propeller, and a beverage coil supported by said cover means in the other tank, said tanks having openings in their upper ends and openings in

their bottoms to which said communicating passages are connected to provide for an end to end flow of the cooling medium out of one tank and into and through the other tank.

5 14. Refrigerating apparatus of the class described comprising, in combination, a pair of tanks having cover means therefor and communicating passages therebetween, an exteriorly supported motor on said cover means, a drive extending through said cover means into one of said tanks, a propeller at the end of said drive, a beverage coil in one of said tanks, a refrigerant coil in the other tank, and inlet and outlet connections for said coils in said cover means and 10 to which said coils are connected for suspended support from said cover means.

15. Refrigerating apparatus of the class described comprising, in combination, a pair of tanks having communicating passages therebetween, means for circulating a cooling medium through one tank and back through the other tank including a motor and a propeller driven thereby, a refrigerant coil in one tank, a beverage coil in the other tank, and a thermostat in 15 said tank containing said beverage coil for controlling said motor, the inlet end of said beverage coil being in the form of a substantially straight tube extending lengthwise of the coil and disposed interiorly thereof to lie substantially parallel to and adjacent said thermostat whereby the incoming beverage flows through 20 said inlet end and past said thermostat before circulating through said beverage coil.

16. Refrigerating apparatus of the class described comprising, in combination, a pair of interconnected tanks, means for circulating a cooling medium through one tank and back through the other tank including a motor and a propeller driven thereby, a refrigerant coil in one tank, a beverage coil in the other tank, and a thermostat 25 in said tank containing said beverage coil for controlling said motor, the inlet end of said beverage coil being in the form of a substantially straight tube extending lengthwise of the coil to lie substantially parallel to and adjacent said thermostat whereby the incoming beverage flows through 30 said inlet end to influence said thermostat before entering said beverage coil.

17. Refrigerating apparatus of the class described comprising, in combination, a pair of interconnected compartments, means for providing a forced circulation of a cooling medium through one compartment and back through the other compartment, a motor for driving said circulation means, a refrigerant coil in one compartment, a beverage coil in the other compartment, and a thermostat in said compartment containing said beverage coil for controlling said motor, the inlet end of said beverage coil lying adjacent 35 said thermostat whereby said thermostat is influenced by the incoming beverage before it completely flows through said coil, there being provisions with respect to said forced circulation of said cooling medium to prevent a thermal circulation when said motor driven means discontinues said forced circulation.

18. Refrigerating apparatus of the class described comprising, in combination, two compartments having communicating passages therebetween, means for circulating a cooling medium through one compartment and back through the other compartment by means of 40 said communicating passages, a motor for driving said circulating means, said communicating passages being so arranged with respect to the

ends of said compartments that the cooling medium circulates substantially longitudinally and centrally through each compartment in a stream of a sectional area substantially equal to the sectional area of each compartment, a refrigerant coil concentrically disposed in one compartment, a beverage coil concentrically disposed in the other compartment, and a thermostat positioned longitudinally within said beverage coil and adjacent the inlet end thereof, the convolutions of said coils being of a diameter allowing the circulating cooling medium to pass centrally through said coils and over their respective convolutions. 5

19. In a refrigerating apparatus of the class described, two tanks having communicating passages, power operated means for providing a forced circulation of a cooling medium substantially longitudinally and centrally through said tanks by way of said communicating passages, 10 and a coil in each tank so arranged therein with respect to said longitudinal central circulation that at least a substantial portion of each coil lies in the circulating cooling medium, there being provision with respect to said communicating passages for preventing a thermal circulation of said cooling medium when said power operated means discontinues said forced circulation. 15

20. In a refrigerating apparatus of the class described, two compartments having communicating passages, power operated means for providing a forced circulation of a cooling medium through said compartments by way of said communicating passages, a refrigerant coil in one of said compartments, a beverage coil in the other compartment, said coils being so arranged in each compartment with respect to said forced circulation that at least a substantial portion of each coil lies in the circulating medium, and a thermostat for controlling said power operated 25 means so positioned in said compartment containing said beverage coil as to be responsive to the temperature of the beverage before it travels from end to end through said beverage coil, there being provisions with respect to said communicating passages for preventing a thermal circulation of said cooling medium when said power operated means discontinues said forced circulation. 30

21. In a refrigerating apparatus of the class described, two compartments having openings at or near their bottom and openings at or near their top, communicating passages connected to said compartments at said openings providing for a forced circulation of a cooling medium 35 through said compartments, a refrigerant coil in one compartment, a beverage coil in their other compartment, said coils being supported in said compartments substantially over said bottom openings, and a motor driven propeller disposed in one of said tanks substantially over its bottom opening for establishing said forced circulation. 45

22. In a refrigerating apparatus of the class described, two compartments having openings at or near their bottom and openings at or near their top, communicating passages connected to said compartments at said openings providing for a forced circulation of a cooling medium through 50 said compartments, a refrigerant coil in one compartment, a beverage coil in their other compartment, said coils being supported in said compartments substantially over said bottom openings, a circulating means positioned in one of 55 said tanks substantially over its bottom opening 60

70

75

for establishing a forced circulation, and a motor for driving said circulating means, said motor and said coils being carried from the top of said compartments.

- 5 23. In a refrigerating apparatus of the class described, two compartments having communicating passages providing for the forced circulation of a cooling medium substantially longitudinally through said compartments, a coil in each compartment so arranged with respect to said longitudinal circulation that at least a substantial portion of each coil lies in the circulating medium as it is forced through said compartments, said communicating passages connecting 10 with said compartments substantially at opposite ends thereof to provide for said longitudinal circulation, and a motor driven device for establishing said forced circulation, said device being located substantially adjacent the opening of one 15 of said communicating passages, said opening being of a width sufficient to substantially receive the moving stream of the cooling medium set up by the operation of said device whereby to effect a substantially complete and continuous displacement of the cooling medium out of one compartment into and through the other compartment.

24. In a refrigerating apparatus of the class described, two compartments having communicating passages, a refrigerant coil in one compartment, a beverage coil in the other compartment, power operated means for providing a 5 forced circulation of a cooling medium between said compartments, said communicating passages being so connected between said compartments as to provide for a through flow of the cooling medium in each compartment, a thermostat for 10 controlling said power operated means, said thermostat being so positioned with respect to said beverage coil as to be responsive to the temperature of the beverage before it travels from end to end through said beverage coil and so positioned with respect to said through flow of the cooling medium as to be influenced by the temperature of the cooling medium as soon as the cooling medium is circulated out of said refrigerant coil compartment and into said beverage 15 coil compartment, there being provisions with respect to said forced circulation of said cooling medium to prevent a thermal circulation when said power operated means discontinues said forced circulation. 20 25

MATTHEW PATRICK FUGLE.
